[57] CLAIM

The ornamental design for a grill stove, as shown and described.

DESCRIPTION

FIG. 1 is a perspective view of a grill stove with the lid closed, showing our new design;

FIG. 2 is a perspective view thereof with the lid open;

FIG. 3 is a perspective view thereof with the lid removed;

FIG. 4 is a top view thereof with the lid open;

FIG. 5 is a top view thereof with the lid closed;

FIG. 6 is a bottom view thereof;

FIG. 7 is a side view thereof;

FIG. 8 is a view of the opposite side thereof;

FIG. 9 is a front view thereof;

FIG. 10 is a back view thereof;

FIG. 11 is a perspective view of another embodiment thereof with the lid in the open position; and,

FIG. 12 is a perspective view of yet another embodiment thereof with the lid in the open position.

The lid is removed in FIG. 3 for clarity of illustration, the claim being drawn to an entire grill stove with lid.

The second and third embodiment show a different grate, the remaining structure being identical to the first embodiment.
